War

Application January 13, 1945, Serial No. 572,718

3 Claims. (Cl. 250—27)

1

This invention relates to impulse energy-operated devices and more particularly to an arrangement for producing substantially fixed delay for all applied impulses. The invention is contemplated to have particular utility in impulse energy-operated systems as are employed for the radio location of aircraft and other mobile bodies where fixed or adjustably controllable delays may be desirable.

It is an object of this invention to provide improved means for effectively delaying a series of impulses recurring periodically or in a more or less random manner, a predetermined amount for each impulse thereof.

Another object of this invention is to provide a device of the above type which will yield delayed impulses of sharply defined form.

Yet another object of this invention is to provide impulse delay apparatus characterized by a high degree of stability and not susceptible to voltage fluctuations in the power supply associated therewith.

A further object of this invention is to provide impulse delay apparatus with relatively flexible means for adjusting the effective delay thereof.

For a better understanding of the invention together with other objects and further features of novelty thereof, reference is had to the following specification taken in connection with the accompanying drawing wherein like parts are indicated by like reference numerals. The scope of the invention will be pointed out in the accompanying claims. In the accompanying drawing,

Figure 1 is a schematic circuit diagram of a preferred embodiment of the present invention.

Figure 2—A is a schematic circuit diagram illustrative of a specific feature of the invention while Figure 2—B shows the discharge characteristics curve of a resistance-capacitance network included in Figure 2—A and,

Figure 3 is a schematic circuit diagram of another preferred embodiment of the present invention.

Referring now to the drawing and more particularly to Figure 1, one preferred embodiment of the invention is shown including a grid-controlled gas-filled tube 10, a diode vacuum tube 11 and a pair of triode vacuum tubes 12 and 13. For purposes of simplicity, tube heaters are omitted from the diagram. Plate voltage for tubes 10, 11, 12 and 13 is provided by "B" battery 14. Shunted across battery 14 is a bleeder network comprising in series connection, variable resistor 15, potentiometer 16 and variable resistor 17.

2

Grid bias for gas-filled tube 10 is furnished by "C" battery 18, the voltage thereof being sufficient to bias the tube 10 beyond cut-off whereby it is normally nonconductive. The anodes of gas-filled tube 10 and diode 11 are tied together and connected to the positive terminal of battery 14 through condenser 19 shunted by resistor 20. The cathode of diode 11 is connected to the sliding arm of potentiometer 16 through the primary winding of a step-up transformer 21. Since initially the anode of diode 11 is at positive potential in respect to the cathode, the tube is normally conductive.

The impulses to be delayed are applied to the input terminals 22 where they are imposed upon the grid circuit of gas-filled tube 10 through capacitor 23. These impulses are of the type shown by form 24 and have a magnitude and a polarity with respect to the grid of tube 10 sufficient to overcome the cut-off bias impressed thereon by battery 18, thereby firing said tube.

When gas-filled tube 10 is fired, the internal impedance thereof is greatly diminished so that condenser 19 in the plate circuit becomes charged to substantially the voltage of battery 14. Thereupon, the charged condenser 19 proceeds to discharge through resistor 20 at a rate determined by the time constant of the network. Since the polarity of charged condenser 19 is negative in respect to the anodes of tubes 10 and 11, gas-filled tube 10 is extinguished and diode 11 is rendered nonconductive.

The effect of the discharge action of condenser 19 upon diode 11, and the circuit components associated therewith, may be understood more clearly by referring to Figures 2—A and 2—B wherein only the active components in connection with diode 11 are shown. It will be assumed, for purposes of explanation, that battery 14 furnishes a potential of 100 volts. Consequently, at the instant of maximum charge, condenser 19 will also store 100 volts. It will be assumed further that the sliding of potentiometer 16 is adjusted so that the cathode of diode 11 is set at a 50-volt tap. It may readily be seen that inasmuch as the negative terminal of the fully charged condenser 19 is connected to the anode of diode 11, the over-all potential on the anode is 50 volts negative in respect to the cathode. Thus, when condenser 19 is in the condition of full charge, diode 11 is rendered nonconductive causing the field in the primary of transformer 21 to collapse thereby inducing a surge of energy in the secondary winding thereof. A condenser 25 is connected between ground and one side of a pri-

mary of transformer 21 acting in combination therewith as a pulse-forming network. Hence, when diode 11 becomes nonconductive, the resultant energy wave in the secondary of transformer 21 assumes a fairly well-defined pulse form.

Referring now to Figure 2-B, the voltage versus time characteristics curve of condenser 19 and resistor 20 is shown. At maximum charge the condenser potential is 100 volts. When at a point along the exponential discharge curve, the charge of the condenser is reduced to 50 volts, it will be seen by referring to Figure 2-A that the plate voltage on diode 11 is now zero in respect to the cathode. If the condenser charge further diminishes beyond the 50-volt point, the plate becomes positive in respect to the cathode and the diode 11 is rendered conductive causing a surge of current through the primary winding of transformer 21 in a direction opposite to the flow occurring when the tube is rendered nonconductive. Thus, a second pulse is produced in the secondary of transformer 21 spaced from the first pulse for a time determined by the non-conduction period of diode 11. It is evident if the cathode of diode 11 were connected to a tap exceeding 50 volts, conduction would occur at a later interval in the discharge curve of condenser 20, whereas if the cathode were connected to a tap providing less than 50 volts, diode 11 would be rendered conductive at an earlier interval in the discharge period.

The voltage applied to the cathode of diode 11 may be adjusted by varying either resistor 15, potentiometer 16, or resistor 17. By varying the cathode voltage, the spacing between the first and second pulse yielded in the secondary of transformer 21 may be controlled. In practice, the settings of variable resistors 15 and 17 preferably are fixed at points whereby the desired range of spacing between the first and second pulse may be effected solely by the adjustment of potentiometer 16.

It is to be noted that if "B" battery 14 is supplanted by a power supply of poor regulation, voltage fluctuations in the output thereof will not influence the predetermined spacing between the first and second pulse. For example, if the voltage of the power supply rises from 100 to 120 volts, the full charge of condenser 19 will likewise rise to 120 volts, while the cathode voltage secured at the arm of potentiometer 16 would then be 60 volts, so that the ratio between cathode and plate voltage in diode 11 would remain undisturbed. As is well known, the characteristics of an exponential condenser discharge are such that condenser 20 will discharge a constant percentage of its voltage in a given time. Consequently, irrespective of its fully charged voltage, which in this instance is either 100 volts or 120 volts, the time at which the condenser is discharged to a 50-volt point in the first case, or a 60-volt point in the second case, is identical since in both cases they are at the half-way discharge level. Diode 11 would then be rendered conductive at the same instant when employing a 120-volt supply as when battery 19 provided 100 volts. Accordingly, within the operating voltage values of tubes 10 and 11, voltage supply fluctuations will not alter the spacing between the first and second pulses yielded in the output of transformer 21.

Referring again to Figure 1, it has been demonstrated thus far that for each impulse applied to the grid of gas-filled tube 10 there is obtained

in the secondary of transformer 21, as illustrated by form 21', a first pulse appearing substantially at the instant diode 11 is rendered nonconductive by the charging of condenser 19, and a second pulse, spaced a predetermined interval from the first pulse and opposed in polarity thereto, which appears when diode 11 again becomes conductive at a selected point during the discharge of condenser 19.

The second or delayed pulse is employed to trigger a blocking oscillator, of novel construction, including triodes 12 and 13 which generates a single sharply defined pulse for each triggering pulse. The circuit of the blocking oscillator is designed so that the first pulse effects no triggering action.

Plate voltage for triode 12 is secured through resistor 26 while plate voltage for triode 13 is obtained through resistor 27. The ohmic value of resistor 26 is relatively high as compared to resistor 27, hence the voltage on the anode of triode 12 is relatively low compared to that of triode 13. The cathodes of triodes 12 and 13 are tied together and connected to ground through resistor 28. The grid of triode 13 is connected to ground through a grid leak 29 having an extremely high resistance. The grid of triode 12 is connected to cathode through the secondary of transformer 21 having a fairly small direct-current resistance. It may be seen that the grid of triode 13 is negative in respect to cathode to a degree determined by the voltage drop across resistor 28, while the grid of triode 12 is substantially at cathode potential. Initially, triode 12 is conductive whereas triode 13 is biased to cut-off.

The secondary winding of transformer 21 is directly connected to the grid and cathode of triode 12 in a manner whereby the first pulse induced therein applies a positive voltage to the grid, while the second or delayed pulse applies a negative voltage to the grid. When a positive voltage appears on the grid of triode 12, plate current flow increases, causing a corresponding drop in plate voltage as a result of the IR drop developed across resistor 26 which, in turn, imposes a negative voltage upon the grid of triode 13 through coupling capacitor 30. Inasmuch as triode 13 is normally nonconductive, the negative voltage appearing on the grid effects no further diminution in current flow. Accordingly, the blocking oscillator is not triggered by positive-going pulses.

When, however, a negative pulse is applied to the grid of triode 12, the flow of current therein is decreased resulting in a rise in plate voltage whereupon a positive surge is applied to the grid of triode 13 rendering said tube conductive. With current flowing through triode 13, the voltage drop across resistor 28 is augmented, thereby effectively decreasing the flow of current through triode 12. The reduction in current flow in triode 12 further increases the voltage on the plate thereof causing an increase in the positive surge applied to the grid of triode 13 through capacitor 30 resulting in a repetition of the effect above described. This regeneration is permitted to continue only for a single cycle because of the voltage drop developed across grid leak 29 when grid current is drawn upon the application of a positive voltage on the grid of triode 13. The grid leak 29 impresses a negative bias on the grid of triode 13 which blocks any further oscillation beyond the first cycle for a period determined by the time constant of capacitor 30 and grid leak 29. The oscillator reverts to its initial condition until

again excited by a negative triggering pulse. Accordingly, for each negative triggering pulse applied to the grid of triode 12 there is generated in triode 13 a pulse which is negative going in the plate circuit and positive going at the cathode. The former pulses are made available at terminals 31 and the latter at terminals 32.

It is sometimes desirable in a delay circuit operating in accordance with the principles underlying this invention to employ tubes of the hard vacuum type in preference to the gas-filled tube 10 shown in Figure 1. It has been found that an error is sometimes introduced in the operation of the delay circuit due to variations in the deionization time of a gas-filled tube when exposed to radio frequency energy. Since the delay circuit may be employed in conjunction with and in proximity to pulse-echo transmitters, a second embodiment of the invention is disclosed in Figure 3 wherein only non-gaseous tubes are included whose operation is not influenced by radio frequency energy.

Referring now to Figure 3, the delay circuit entails the use of three diode vacuum tubes 33, 34 and 35 and a blocking oscillator employing a pair of triode vacuum tubes 36 and 37. Since the blocking oscillator is identical both in design and operation with that disclosed in connection with Figure 1 including tubes 12 and 13, it will not be necessary to review the explanation of its theory of operation. Plate voltage for tubes 33 to 37 is furnished by a "B" battery 38. Shunted across battery 38 is a bleeder series network consisting of variable resistor 39, potentiometer 40 and variable resistor 41. The plate of diode 33, the cathode of diode 34, and the plate of diode 35 are tied together and connected to one side of the secondary of a step-up transformer 42 through a condenser 44 shunted by a resistor 45. The other side of the secondary of transformer 42 is connected to the cathode of diode 33. The plate of triode 36 is directly connected to ground while the cathode of diode 35 is connected to the sliding arm of potentiometer 40 through the primary of a step-up transformer 43.

The incoming impulses to be delayed are applied to terminals 46 where they are fed to the primary of transformer 42. The polarity of incoming impulses is made such whereby the impulses induced in the secondary of transformer 42 apply a positive potential to the plate of diode 33 with respect to the cathode thereof which renders diode 33 conductive thereby charging condenser 44. The pulses in the secondary of transformer 42 as shown by form 47 are of such amplitude as to exceed in potential the voltage provided by battery 38. When condenser 44 is charged, its negative terminal is connected to the plates of diodes 33 and 35 and the cathode of diode 34. If the charge on condenser 40 exceeds the potential of battery 45, the cathode of diode 34 becomes negative in respect to the plate thereof and the tube conducts to ground. Thus, regardless of the magnitude of the voltage applied to condenser 40, the charge thereon can never exceed the voltage of battery 38 since beyond that point tube 34 conducts to ground. For that reason the amplitude of applied impulses may vary without affecting the maximum charge stored by condenser 45 as long as the minimum impulse exceeds in magnitude the voltage of battery 38.

Condenser 44 proceeds to discharge through resistor 45 and diode 35 is rendered nonconductive since the potential at the plate is now negative.

ative in respect to the cathode. When diode 35 is rendered nonconductive the collapsing field in the primary of transformer 43 induces a surge of energy in the secondary thereof which is shaped into a fairly well defined pulse form by the presence of capacitor 48 connected between one side of the primary of transformer 43 and ground, the combination serving as a pulse forming network. At the point in the exponential discharge curve of condenser 44 where the plate of diode 35 becomes positive in respect to cathode, the diode is again rendered conductive and a current surge flows in the primary of transformer 43 which induces a second pulse in the secondary thereof spaced from the first pulse and opposed in polarity thereto as shown by form 49.

The secondary of transformer 43 is connected between the grid and cathode of triode 36 in a manner whereby the second or delayed pulse applies a negative potential to the grid thereby triggering a blocking oscillator in the manner described hereinabove in connection with Figure 1. Negative going delayed pulses of the type shown by form 50 are obtained at terminals 51 coupled to the plate circuit of tube 37 while positive going delayed pulses as shown by form 51 are made available at terminals 52 coupled to the cathode circuit of tube 37.

It will be seen that there has been disclosed relatively simple means for effectively delaying recurrent impulse energy. Although this delay is attained by generating new impulses for those applied, the arrangement shown has the advantage of producing extremely sharp and well defined impulses at the output waves. If some passive network had been employed to obtain the delay there would have been substantial distortion of the original applied wave form and it accordingly would have been increasingly difficult to attain a well defined delayed pulse, the larger the delay. If it be desired to produce delayed impulses of the same form as those applied to the input, the delayed impulses produced by the circuit shown may be used to synchronize a wave generator having suitable shaping means and by monitoring input pulse shapes and shaping the newly generated pulse shapes to conform thereto, the effect of flexibly adjustable delay is produced with no apparent distortion.

Although the delay has been disclosed to be adjustably controllable by controlling the voltage applied to the cathode of diode 11, it is to be understood that the delay adjustment may be effected by other means. For example, the ohmic value of resistor 20 shunting condenser 19 in Figure 1 or resistor 45 shunting condenser 44 in Figure 3 may be adjusted thereby varying the delay of the circuits. While this invention has been described as being particularly adaptable to the delaying of time-modulated impulse energy, it is clear that it may be equally applicable to systems employing frequency modulation impulses, that is, impulses whose frequency of recurrence is modulated in accordance with a given signal.

Although throughout the above specification and in the annexed claims reference has been made to the type of energy which was fed to the apparatus as impulse energy, it is to be understood that this term embraces impulses in a broad aspect, that is, not only the relatively short abrupt form as shown by form 24 in Figure 1 but also any type of electrical fluctuation.

While there have been described what are at present considered preferred embodiments of the

invention, it will be obvious to those skilled in the art that various changes and modifications may be made therein without departing from the invention, and it is, therefore, aimed in the appended claims, to cover all such changes and modifications as fall within the true spirit and scope of the invention.

We claim:

1. Apparatus for producing output impulses delayed a predetermined amount of time with respect to input triggering impulses comprising a source of direct-current potential having an intermediate tap, a resistance-capacitance parallel network having one terminal connected to the positive pole of said source, a diode discharge device having an anode and a cathode, means connecting said anode to the other terminal of said network, means connecting said cathode to said intermediate tap whereby said diode is initially conductive, means responsive to a triggering impulse and independent of its duration to couple momentarily the negative pole of said source to said other terminal of said network whereby said network is instantly charged to substantially the full potential of said source, thereby rendering said diode nonconductive for a period determined by the time constant of said network, and means to develop an output impulse at the moment said network is discharged to the level at which said diode is again rendered conductive, said means for developing an impulse comprising a step-up transformer having a primary winding and a secondary winding, said primary winding being interposed between said cathode and said intermediate tap, a capacitor connected between said intermediate tap and said negative pole, said capacitor in combination with said primary winding being adapted to act as an impulse-forming network, whereby an output impulse is induced in said secondary winding at the moment said diode is rendered conductive or nonconductive.

2. Apparatus for producing output impulses delayed a predetermined amount of time with respect to input triggering impulses comprising a source of direct-current potential having an intermediate tap, a resistance-capacitance parallel network having one terminal connected to the positive pole of said source, a diode discharge device having an anode and a cathode, means connecting said diode anode to the other terminal of said network, means connecting said diode cathode to said intermediate tap whereby said diode is initially conductive, a gas tube having an anode, a cathode, and a control grid, said gas tube anode being connected to said other terminal of said network, said gas tube cathode being connected to the negative pole of said potential source, means for applying a triggering impulse to said gas tube grid and independent of the duration of said triggering impulse to fire said tube, thereby instantly charging said network to substantially the full potential of said source

whereby the potential at the anode of said gas tube decreases to an extent where said gas tube is extinguished and said diode is rendered nonconductive for a period determined by the time constant of said network, and means for developing an output impulsive at the moment said network is discharged to the level at which said diode is again rendered conductive.

3. Apparatus for producing output impulses delayed a predetermined amount of time with respect to input impulses comprising a source of direct-current potential having an intermediate tap, a resistance-capacitance parallel network having one terminal connected to the positive pole of said source, a diode discharge device having an anode and a cathode, means connecting said diode anode to the other terminal of said network, a step-up transformer having a primary winding and a secondary winding, one side of said primary winding being connected to said intermediate tap, the other side of said primary winding being connected to said diode cathode whereby said diode is initially conductive, a gas tube having an anode, a cathode and a control grid, said gas tube anode being connected to said diode anode, said gas tube cathode being connected to the negative pole of said potential source, means for applying a triggering impulse to said gas tube grid, and independent of the duration of said triggering impulse, to fire said gas tube, thereby instantly charging said network to substantially the full potential of said source whereby the potential at the anode of said gas tube decreases to an extent where said gas tube is extinguished and said diode is rendered nonconductive for a period determined by the time constant of said network, a capacitor connected between said intermediate tap and said negative pole, said capacitor in combination with said primary winding of said transformer being adapted to act as an impulse-forming network whereby an output impulse is induced in said secondary winding at the moment said diode is rendered conductive or nonconductive, and means for adjusting the position of said intermediate tap in said source of potential whereby the time delay of said output impulse with respect to said triggering impulse may be adjusted.
